PUMP

Theodore R. Thoren, Chagrin Falls, Leslie L. Aspelin, Cleveland Heights, and John F. Murray, Macedonia, Ohio, assignors to Thompson Products, Inc., Cleveland, Ohio, a corporation of Ohio

Application June 15, 1949, Serial No. 99,186

11 Claims. (Cl. 103—117)

1.

This invention relates generally to positive-displacement rotary pumps and more particularly to improvements in a flexible rotor positive-displacement pump of the type including a rubber rotor having a plurality of radial resiliently flexible vanes or blades therearound and defining pumping chambers therebetween. The rotor is mounted in a pump bore shaped to sealingly engage the outer ends of the vanes and to deform the vanes as they pass from the pump outlet to the inlet for sealing against leakage from the outlet back to the inlet.

In heretofore provided flexible rotor pump assemblies, certain difficulties have been encountered in connection with sealing the rotor and controlling the rotor end thrust. For example, regulation pump shaft seal units have relatively large cup-like casings which are press-fitted into the pump casing and require large diameter chambers to receive them. These chambers, however, cannot exceed the root or hub diameter of the pump rotor without joining the inlet and outlet ports of the pump. Therefore, it has been necessary to either use an inefficient small diameter seal or to increase the rotor hub diameter, thereby decreasing the pumping capacity and efficiency of the pump.

The present invention provides a novel and improved sealing assembly which employs a unique filler plate for correcting the difficulties aforementioned. The filler plate is accurately formed from cartridge brass and is snugly seated in one end of the bore of the rotor chamber to abut the flexible rotor and close off a possible path joining the inlet and outlet ports through the seal chamber.

The opposite end of the rotor chamber is also provided with a thrust plate accurately formed from cartridge brass and snugly seated in a recess in the bore of the rotor chamber in abutting relationship to the flexible rotor.

The employment of our novel seal assembly also affords a novel and improved rotor assembly capable of achieving self-alignment as controlled by the fixed distance between the filler plate and the thrust plate. Thus the body casting defining the pumping cavity for the flexible rotor slidably receives a bearing assembly carrying the rotor shaft and therefore the rotor finds its own position between the thrust and filler plates in the pumping cavity.

The pump casing is closed with a gasket and cover which act upon the thrust plate, but, since the distance between the thrust and filler plates is fixed, the end clearance of the pump rotor is not affected by variations in tolerances which

2.

are absorbed by gasket compression in the areas where the gasket contacts the thrust plate.

The present invention also provides a liquid seal for the rotor chamber and uses the end cover and thrust plate to bleed deaerated liquid from a standpipe chamber back to the rotor chamber to lubricate the chamber. The standpipe chamber receives the pump discharge and provides a head of liquid that will fill the spaces between the pump vanes with an inelastic medium as they pass between the outlet and inlet ports and thereby maintain a high suction pull at the inlet.

It is, therefore, an object of this invention to provide a rotor support and seal assembly for a rotor positive displacement pump whereby the rotor positions itself and is not influenced by variable gasket compression.

Another object of this invention is to provide an efficient sealing arrangement for a flexible rotor positive displacement pump including novel elements for sealing the rotor chamber which are capable of receiving end thrusts without the detrimental effects of erosion.

A further object of this invention is to provide a standpipe for water-sealing and lubricating a flexible-rotor positive-displacement pump.

Many other objects and advantages of the present invention will become manifest to those versed in the art upon making reference to the detailed description which follows, and the annexed sheets of drawings in which—

Figure 1 is an end elevational view of the cover end of a flexible rotor positive displacement pump embodying the principles of our invention;

Figure 2 is a fragmentary end elevational view of a portion of Figure 1 with the cover removed;

Figure 3 is a side elevational view of the pump shown in Figure 1;

Figure 4 is a fragmentary cross-sectional view taken on line IV—IV of Figure 1;

Figure 5 is a cross-sectional view taken on line V—V of Figure 1; and

Figure 6 is a cross-sectional view taken on line VI—VI of Figure 5.

As shown on the drawings:

Referring first to Figures 1 and 3, a flexible rotor positive displacement pump is indicated generally by the reference numeral 10 and is shown as including a body 11 and a cover 12, both made of light weight metal die castings such as aluminum castings. The cover 12 may be drawn up in firm assembly with the body 11 by means of a plurality of fasteners 13 threaded 50 into a flange formed on the body 11.

As may be most clearly seen on Figure 6, the

body 11 is formed as an integral unit to define a rotor cylinder 14 defining an axially tapered cam shaped bore 15 which serves as a pumping cavity for a flexible rotor.

The body 11 further defines an inlet port 18 and a discharge port 19, both being in communication with the bore 15 of the rotor cylinder 14.

The body 11 is shaped in such a manner as to form a standpipe cavity 20 inside a casing which extends upwardly from the rotor cylinder as at 11a and around to join a lower portion of the rotor cylinder 14 as at 11b.

An outlet 21 spaced above the discharge port 19 is formed in an upper portion of the body 11. The standpipe cavity 20 is divided by a baffle 22 joined to the rotor cylinder 14 at a point below the discharge port 19 in such a manner as to divide the standpipe cavity 20 into a so-called turbulent area 20a and a quiescent area 20b. In other words, the baffle 22 is located in such a manner as to isolate a portion of the standpipe cavity 20 in the locale of the discharge port 19, thereby permitting a substantial portion of the standpipe 20 to contain fluid in a comparatively non-turbulent condition.

It should be apparent that since the pump 10 is maintained in an upright position, fluid emanating from the discharge port 19 will necessarily enter the turbulent area 20a and will eventually overflow the top of the baffle 22. By virtue of the overflow action over the baffle 22, the water in the quiescent area 20b will, in effect, be deaerated and the quiescent area 20b will thereby constitute a standpipe filled with deaerated, non-turbulent inelastic fluid. Since the outlet 21 is located in an upper portion of the body 11 and is spaced above the discharge port 19, an adequate head of fluid will always be maintained in the standpipe 20.

As may be seen in Figures 3 and 5, the body 11 is provided with a drain aperture 23 in a lower portion thereof closed by a removable drain plug 24 threadedly received therein.

Referring now particularly to Figure 5, it will be noted that one end of the rotor cylinder 14 defined by the body 11 is shaped in such a manner as to define an essentially cylindrical bore or bearing race 26 adapted to slidably receive a ball bearing assembly 27. A shaft 28 is press-fitted into the bearing assembly 27 and its end is press-fitted in a rotor insert or bushing 29.

A flexible rotor 17 made of a resilient material such as molded rubber or the like and defining a plurality of spaced blades 17a is molded or cemented on the rotor insert or bushing 29 and is disposed within the pumping cavity or the bore 15 defined by the rotor cylinder 14. The end of the rotor insert or bushing 29 may define a threaded hole to facilitate withdrawal of the bushing from the shaft 28 by turning in a screw.

Figure 6 shows that the arrangement of the flexible rotor 17 within the eccentric bore 15 is such as to flexibly deform the blades 17a of the rotor 17 upon rotation thereof so that the blades will collapse inwardly to fill the space defined between each pair of blades when each of said spaces is approximately in registry with the discharge port 19. Thus, any fluid carried in such space will be subjected to an increased pressure resulting in the expulsion thereof outwardly through the discharge port 19.

Conversely, when the blades 17a, after rotation through bore 15, are again free to resume

their extended position because of their inherent resilience, the space between each pair of blades 17a will progressively increase in volume as such space is placed in registry with the inlet port 18. This action will produce a suction effect, thereby promoting suction head at the inlet port 18. Fluid entering the inlet port 18 will, therefore, be carried around the pumping cavity or bore 15 in the spaces between the blade 17a of the rotor 17 to the discharge port 19.

Figure 5 shows a sealing arrangement which includes a stationary cup 30 positioned on a shoulder 11c of the casing. An annular ring 31 made of resilient material and having flanged portions for seating a resilient member or coiled spring 32 is carried within the cup 30. An annulus 33 of packing material is placed in abutting relationship to the ring so as to be spring biased by the spring 32 against the end of the bushing 29.

It will be noted in Figure 5 that the pumping cavity defined by the bore 15 in the rotor cylinder 14 is terminated by an annular shoulder portion 11d. The flexible rotor 17 is preferably of such a longitudinal dimension as to terminate short of the shoulder 11d when placed in the pumping cavity or bore 15. A filler plate 34 made of cartridge brass and accurately shaped to define the cross-sectional contour of the bore 15 is placed in surrounding relationship to the bushing 29 to abut the shoulder 11d.

In this manner, even though the diameter of the stationary cup 30 exceeds the root diameter of the flexible rotor, the filler plate 34 seals the end of the bore 15 and precludes the passage of fluid through the seal chamber between the inlet port 18 and the discharge port 19.

The filler plate 34 of cartridge brass may be fabricated as a stamping and displays exceptionally favorable wearing characteristics inasmuch as the abutting relationship between the filler plate 34 and the flexible rotor 17 actually improves the polish of the filler plate with use.

Referring now to Figures 2 and 5, it will be noted that the other end of the bore 15 is provided with a shouldered recess 11e and a thrust plate 36 also formed of cartridge brass snugly fits into this recess to bottom on the shoulder thereof. The pumping cavity of the bore thus has a fixed length between the plates 34 and 36. A recirculating port or auxiliary inlet port 36a is formed in the thrust plate 36 and is disposed in such a manner as to lie at a portion of the pumping cavity intermediate the inlet port 18 and the discharge port 19 but ahead of the discharge port 19.

The cover 12 is provided with a recess 37 which defines a bleeder passage or connection from the standpipe cavity 20b to the recirculating port or auxiliary inlet port 36a formed in the thrust plate 36.

A gasket 38 made of a suitable compressible material is provided between the cover 12 and the body 11 and is shaped in such a manner as to overlie the edges of the body 11 and to abut the thrust plate 36.

Since the shaft 28 of the rotor 17 is press-fitted in the ball bearing assembly 27 and the outside race defined by the bore 26 provides a sliding fit in the body 11 for the ball bearing assembly 27, the rotor 17 will be free to find its own position in the pumping cavity defined by the bore 15 between the fixed plates 34 and 36. Thus, tolerance variations in the assembly can be absorbed

by compression of the gasket without varying the distance between the plates. The desired and clearance or rubbing contact with the plates will therefore be maintained.

It has been found that the brass plates 34 and 36 display unusually favorable wearing characteristics.

It will be noted that discharge fluid contained in the quiescent area 20b of the standpipe cavity 20 will bleed into the pumping cavity through the recirculating aperture or auxiliary inlet port 36a formed in the thrust plate 36 by way of the recess 37 formed in the cover 12 and will lubricate the bore 15. This liquid bleed arrangement and the maintenance of a liquid head above the port 19 will also fill the spaces between the vanes with liquid as they pass from the outlet 19 to the inlet 18, thereby maintaining a good seal and minimizing expansion at the inlet.

It will thus be apparent from the above descriptions that this invention provides a flexible rotor pump with a self-aligning rotor between plates which coat with a pump seal and bleeder passage for maintaining discharge liquid in the pump bore to augment the sealing efficiency of the seal.

It will, of course, be understood that various details of construction may be varied through a wide range without departing from the principles of this invention, and it is, therefore, not the purpose to limit the patent granted hereon otherwise than necessitated by the scope of the appended claims.

We claim as our invention:

1. A flexible rotor pump comprising a casing defining a standpipe chamber and a pumping chamber and having an open end exposing said chambers, a removable cover for said open end, a compressible gasket between the cover and casing, fasteners for tightening the gasket and cover against the casing to seal the chambers from each other and to seal the casing, said pumping chamber having aligned inlet and outlet ports at the upper end thereof with the outlet port discharging into the standpipe chamber intermediate the top and bottom thereof, a baffle in the standpipe chamber underlying the outlet port and extending upwardly to a level above the outlet port to divide the chamber into a turbulent area portion and a quiescent area portion, said standpipe chamber having an outlet in the upper portion thereof, said casing having a bearing chamber axially aligned with the pumping chamber, a bearing slidably in said bearing chamber, a rotor shaft carried by said bearing, a rotor carried by said shaft in said pumping chamber and having flexible vanes defining pumping spaces therebetween, plates bottomed in opposite ends of the pumping chamber defining a fixed dimension length therebetween and receiving the end thrust of the rotor and sealing the ends of the pumping spaces, a shaft seal between the bearing and rotor, and aligned bleeder passages in the cover and adjacent plate joining the quiescent area of the standpipe with the pumping spaces to maintain liquid therein for sealing and lubricating the rotor and minimizing expansion at the pump inlet whereby said gasket will yield to tolerance variations when the fasteners tighten the cover but said fixed end plates will prevent variations in the relationship of the rotor and plates.

2. A flexible rotor pump assembly including a casing having a standpipe chamber, a pumping chamber with an outlet port at the upper por-

tion thereof discharging into the standpipe chamber and a bearing chamber axially aligned with the pumping chamber, a slidable bearing in the bearing chamber, a rotor shaft carried by the bearing, a rotor on the shaft having flexible vanes defining pumping spaces therebetween and arranged to be rotated in the pumping chamber, a seal plate bottomed in the pumping chamber and closing the ends of the pumping spaces to partition the bearing and pumping chambers, a thrust plate bottomed in the other end of the pumping chamber, a spring pressed shaft seal between the bearing chamber and seal plate and acting on the rotor to urge the rotor against the thrust plate, an end cover and gasket closing the casing, and communicating passages in the end cover and thrust plate joining the bottom of the standpipe chamber with the pumping chamber below the outlet port.

3. A pump comprising a body defining a rotor cylinder having a cam-shaped bore with an inlet port and a discharge port, and further defining an enclosed cavity adjacent said rotor cylinder on the discharge port side, a flexible rotor defining a plurality of circumferentially spaced radially extending resilient blades deformable upon rotation in said bore to pull a suction at said inlet port and produce a discharge pressure at said discharge port, an outlet spaced from said discharge port and formed in an upper portion of said body, a baffle plate in said cavity extending into the region between said outlet and said rotor cylinder and arranged to extend above said rotor cylinder whereby a substantial portion of said cavity including a portion above the level of said rotor cylinder may be filled with non-turbulent fluid from said discharge port, and a bleeder connection in communication with the non-turbulent portion of said cavity and a portion of said eccentric bore in said rotor cylinder intermediate said inlet port and said discharge port, whereby said flexible rotor may be sealed and lubricated with an inelastic deaerated fluid.

4. In a pump, a body defining a rotor cylinder having a bore with an inlet port and a discharge port and further defining a vented cavity adjoining said rotor cylinder in communication with said discharge port, a rotor defining a plurality of spaced flexible blades deformable when rotated in said bore to pull a suction at said inlet port and to produce a discharge pressure at said discharge port, a filler plate at one end of said bore surrounding the shaft of said rotor, a thrust plate in the other end of said bore, said thrust plate defining a port into said bore intermediate said inlet and discharge ports, a gasket on said body and a cover for said body to abut said thrust plate, and said cover defining a bleeder passage from said cavity to said port in said thrust plate, whereby said bore may be provided with fluid from said cavity to seal and lubricate said flexible blades of said rotor.

5. In a pump assembly, a body and a cover cooperatively assembled and forming a pumping cavity having an inlet port and a discharge port and further forming a standpipe cavity adjacent to and in communication with the discharge port of said pump, said body having an outlet spaced above said discharge port, a baffle plate in said standpipe cavity substantially interposed between said outlet and said discharge port and blocking the direct flow of fluid therebetween, said cover having a bleeder passage extending from a portion of the standpipe cavity

on an opposite side of the baffle from said discharge port to a portion of the pumping cavity intermediate the inlet and discharge ports of said pump, said pumping cavity lying below the level of said baffle in said standpipe cavity for continuous flooding thereof by the discharge of said pump and said bleeder passage operative to provide the pumping cavity with non-turbulent inelastic sealing and lubricating fluid from the discharge side of said pump.

6. In a positive displacement pump, a casing having a rotor cylinder and a standpipe cavity adjoining the rotor cylinder, said rotor cylinder having a discharge port and an inlet port, said cavity lying in communication with the discharge port of said rotor cylinder, said casing having an outlet and having a baffle plate blocking direct flow from said discharge port to said outlet and dividing said standpipe cavity into a turbulent area chamber in the locale of said discharge port and a quiescent area chamber below said outlet, and said casing having a bleeder passage formed therein in communication with a portion of the rotor cylinder intermediate the discharge and the inlet ports of said rotor cylinder and said quiescent area, whereby fluid emanating from said discharge port will be deaerated and recirculated through said standpipe cavity and said bleeder passage to seal and lubricate the rotor in the rotor cylinder of said pump and will fill said standpipe cavity to continually flood the rotor cylinder.

7. In a pump, a casing having formed therein an enlarged pumping chamber and a smaller bearing chamber coaxially aligned therewith, a flexible vane rotor having a plurality of pumping spaces between the vanes in said pumping chamber, a shaft connected to said rotor and extending outwardly through said bearing chamber, a bearing journaling said shaft in said bearing chamber of said casing, an annular shoulder at one end of said pumping chamber, a plate abutting said shoulder and being complementary in shape to the contour of said pumping chamber, said plate being engageable with the flexible vanes to close the ends of the pumping spaces and a seal between said bearing and said rotor, said seal including a cup-shaped housing member firmly assembled in said casing and being of greater diameter than the root diameter of said rotor, said seal further including spring-pressed sealing elements of smaller diameter than said housing and engageable with said rotor.

8. A rotor and seal assembly for a flexible rotor positive displacement type pump comprising a body casing having an end face intersected by an enlarged pumping cavity, said end face having a counterbore therein around said cavity, a rotor in said pumping cavity, a cover engaging said end face of said casing enclosing said pumping cavity, a thrust plate in said counterbore and corresponding in shape to the configuration of the pumping cavity, said thrust plate engaging one side of said rotor, an elastic gasket between said body casing and said cover and including portions overlying the body casing and abutting the thrust plate, means to draw said cover into firm assembly with said body casing, said gasket being elastically yieldable to tolerance variations, and spring pressed sealing means at the other side of said rotor bottomed against said body casing for engaging said rotor against said thrust plate independently of the degree of compression of the gasket by the cover, whereby said rotor is self-aligning in said pumping cavity.

9. In a pump, a casing having formed therein a bore, an enlarged pumping chamber in one end of said bore and a smaller bearing chamber in the other end of said bore, an annular shoulder between said two chambers, a flexible vane rotor having a plurality of pumping spaces between the vanes rotatable in said pumping chamber, a shaft connected to said rotor and extending outwardly through said bearing chamber, a bearing journaling said shaft in said bearing chamber of said casing, a shaft seal between said casing and one end of said rotor and a thrust plate shaped complementary to the shape of said pumping chamber engaging the other end of said rotor and sealing said pumping spaces, said seal having spring pressed sealing elements engaging said rotor inside the root diameter thereof and being bottomed against said shoulder to load said rotor against said thrust plate.

10. A pump, comprising, a casing open at one end, a first counterbore in said open end of said casing, a second counterbore in said casing adjacent said first counterbore and providing a pumping chamber, a bearing chamber in said casing adjacent said pumping chamber, a thrust plate in said first counterbore and closing one end of said pumping chamber, a cover connected to said casing closing said open end of said casing, a second plate in said second counterbore at the other end of said pumping chamber, said first and second plates providing a fixed dimension cavity therebetween, a rotor in said cavity and having a shaft extending into said bearing chamber for journaling support therein, and a spring pressed shaft seal in said casing adjacent said second plate and biasing said rotor into running engagement with said thrust plate.

11. In a pump, a casing having a pumping chamber open at one end and having a counterbore inwardly of said one end, rotary fluid displacement means in said pumping chamber, a thrust plate received in said counterbore and having running engagement with said rotary fluid displacement means, a cover closing said open end of said casing, a gasket between said casing and said cover having portions extending between the thrust plate and said cover, said thrust plate and said counterbore providing confronting abutment surfaces limiting inward movement of the thrust plate by compression of said gasket portions between said cover and said thrust plate independent of the degree of the gasket between the casing and the cover.
